UNITED STATES PATENT OFFICE

ROBERT E. MANLEY, OF YORK, PENNSYLVANIA, ASSIGNOR TO MANLEY MANUFACTURING COMPANY, OF YORK, PENNSYLVANIA, A CORPORATION OF DELAWARE

WINCH CRANE

Application filed October 3, 1925. Serial No. 60,229.

This invention relates to hoisting mechanism in general and in particular to wrecking outfits particularly applicable to the raising and bringing into the garage of a disabled automobile.

The principal object of the present invention is to provide a simple and efficient hoisting mechanism of the type described by which an automobile may be pulled out of a ditch 10 by one windlass operating at one rate of power and later be raised from the ground by another windlass operating at a different leverage but from the same source of power thus permitting the simultaneous use of both 15 the usual chain hoist and a cable winch. Other objects of the present invention lie in the particular arrangement of specific elements of the crane and are particularly pointed out in the claims.

20 In the drawings:—

Figure 1 is a side elevation.

Figure 2 is a front elevation and

Figure 3 is a cross section.

The superstructure of the crane consists 25 preferably of a truss which includes a pair of channels 10 secured together at their lower or rear end as by the bolt 11 and pivoted to the frame proper as by the king pin 12. The support or frame is built up of two trusses each 30 formed of two sloping angle irons 15 supporting at their apex a plate 17 secured to each angle iron as by the bolts 18 and carrying a small bracket 19 furnishing a bearing for the main drive shaft 20. The angle irons of 35 each pair are connected at the bottom by members 22 shown as angle irons and these in turn are bolted or riveted to the transverse channels 24 which are intended to be secured on the bed or body of an automobile repair 40 truck so that the front end of the superstructure extends over the rear edge of the automobile bed.

A central shaft 30 is mounted in bearings 45 in the two horizontal cross brackets 31 each bolted to the two sloping members of one of the triangular trusses forming the frame of the hoist. Fast on this shaft 30 is the hub 32^a of a gear 32 in mesh with a pinion 34 keyed to the main shaft 20. A chain hoist 50 drum 35 is loosely mounted on the shaft 30 be-

tween the two trusses and may be operatively connected to the gear 32 and therefore to the shaft 30 by means of a lock pin 36 sliding freely thru a bore in a block 37 integral with one rim of the drum and into a socket 38 in 55 the hub 32^a and this pin may preferably be held in position by a small thumb screw 39. A pinion 40 is loosely mounted on the central shaft 30 on the outside of the bracket 31 but may be locked to the shaft by a clutch of any 60 kind as for example the simple pin 41.

The winch shaft 45 is mounted in brackets 46 bolted to a forward sloping leg 15 of each truss. Preferably I permanently secure to this shaft both the winch drum 47 and the 65 winch gear 48 so that when the pinion 40 is in place the winch is driven with the turning of the shaft 20 by means of the adjustable length handle 50 illustrated which handle may be slipped on either projecting end of the shaft 20 or on either projecting end of the auxiliary shaft 53 carried in brackets 54. On this shaft 53 is keyed a pinion 56 preferably of just the same size as the pinion 34.

The pawl 60 pivoted to one of the upper 70 bolts 18 has a rather heavy angular handle 61 serving normally to hold the pawl in engagement between the teeth of the pinion 34. I find it convenient to perforate this handle to receive a pin 66 which may be pushed inwardly so as to engage with either the upper or the lower surface of the flange of the angle iron 15, in one position holding the pawl 75 in mesh with the pinion and in the other position holding the pawl out of mesh.

The operation of the device is as follows:— Assuming that the automobile has slid down a bank at perhaps a considerable distance from the nearest convenient location of the wrecking truck; the winch cable, one end of which is held in the bore 70 by the set screw 71, is rapidly paid out by freeing the winch drum 47 from the hoist drum mechanism either by releasing the pinion 40 so as to slide it out of mesh with the winch gear 48, or 95 preferably by lifting the lock pin 36 out of its bore or cavity 38 in the hoist drum gear 32 and by raising the pawl 60 out of engagement and holding it so, and slipping in the pawl locking pin 66 so as to have it en- 100

gage the outer flange of the sloping side piece 15 of the triangular truss.

When the free end of the winch cable with its usual gripping means (not shown) is secured to the disabled automobile the cable is wound on the winch and the automobile dragged toward the crane by revolving either end of either the main shaft 20 or the auxiliary shaft 53, whichever happens to be most convenient and the handle proper may be secured at the desired distance from the axis of the shaft by sliding the handle lever bar in its socket in the usual fashion so as to increase or decrease the leverage. Preferably during the winding of the winch drum the pawl is released.

It frequently happens that during part of the dragging forward of the automobile it is necessary to raise it while dragging it. This is taken care of by fastening to it the free end of the chain, one end of which passes over the usual hoist pulleys at the upper end of the truss 10, and it then secured to the hoist drum 35, and by slipping the lock pin 36 back in place we may draw up on the automobile, in other words we may operate both drums simultaneously. When the hoist drum 35 is locked under load by means of the pawl 60 and it is desired to operate the winch independently, this is taken care of by freeing the pinion 40 and then revolving the winch drum 47 by means of the handle 77 carried by it.

In case either drum is used alone the full drive is from the shaft 20 or 53 thru the pinion 34 to 56, as the case may be, to the hoist shaft gear 32 which always revolves whenever the main or the auxiliary shaft revolves. In case the hoist only is to be driven the drum 35 is made fast to the shaft by inserting the pin 36 or if the winch is to be driven the pin 36 is released letting the drum 35 idle while the drive is now from the shaft 30 thru the pinion 40 to the winch gear 48 fast on the winch shaft and therefore always revolving with winch drum which likewise is fast on this shaft.

What I claim is:

1. In an automobile wrecking winch crane, a supporting frame, a drive shaft mounted in said frame, a driven shaft geared thereto carried by said frame, a hoist drum loosely mounted on said driven shaft, clutch means for connecting said hoist drum to said shaft whereby the drum may be driven from said driving shaft or said driven shaft may be rotated without driving the hoist drum, a pinion gear loosely mounted on said driven shaft, means for securing said pinion gear to be driven by said shaft, a second driven shaft carried by said frame, a gear fast thereon and meshing with said pinion gear whereby said second driven shaft will be driven whenever said pinion gear is in secured relation on its shaft, and a winch drum secured to said sec-

ond drive shaft, a gear fast on the second driven shaft and meshing with the hoist drum shaft whereby either the hoist drum or the winch drum may be operated independently by the operation of said drive shaft or they may be connected for simultaneous operation by the drive shaft. 70

2. In a hoist, a frame composed of a pair of trusses each having a pair of sloping angle iron sides joined at their top, a bracket connecting the two angle members of each truss, a central shaft mounted in said brackets, a drive shaft mounted at the apex of each truss, gearing operatively connecting the central shaft and the drive shaft, a pawl pivoted near the apex of one of said trusses so as to engage said gearing, and a sliding pin carried by said pawl engageable with one side or the other of the flange of one of said angle irons for holding said pawl in or out of engagement with said gearing. 85

3. In a hoist, a pair of triangular trusses each having sloping angle iron sides, a shaft below the apexes of the two trusses, a pawl pivoted near one of said apexes, a pinion on said shaft and in the path of said pawl, and a pin loosely mounted in said pawl to engage one of said angle iron sides to hold said pawl in locking engagement with said pinion or to hold the pawl in released position out of engagement with said pinion. 95

In testimony whereof I affix my signature.
ROBERT E. MANLEY.
